UNITED STATES PATENT OFFICE

172,255

BUILDING

Ferdinand J. Toole, Pittsburgh, Pa.

Application July 31, 1953, Serial No. 26,211

Term of patent 7 years

(Cl. D13—1)

To all whom it may concern:

Be it known that I, Ferdinand J. Toole, a citizen of the United States of America, residing at Pittsburgh, Pennsylvania, have invented a new, original, and ornamental Design for Buildings, of which the following is a specification, reference being had to the accompanying drawing, forming a part hereof.

Figure 1 is a perspective view of a building embodying my design.

Fig. 2 is a side elevational view thereof.

Fig. 3 is a rear view of the building, partly broken away.

Fig. 4 is an enlarged sectional view taken on the line 4—4 of Fig. 3, through somewhat more than one-half of the tower.

I claim:

The ornamental design for a building, as shown.
